CLAIM

The ornamental design for a travel mug, as shown and described.

DESCRIPTION

FIG. 1 is a perspective view of a travel mug according to the present invention;

FIG. 2 is a left side view thereof;

FIG. 3 is a right side view thereof;

FIG. 4 is a top view thereof;

FIG. 5 is a bottom view thereof;

FIG. 6 is a rear view thereof;

FIG. 7 is a front view thereof;

FIG. 8 is a perspective view of [an alternate embodiment of the present invention] a travel mug showing a second embodiment of my new design;

FIG. 9 is a left side view thereof;

FIG. 10 is a right side view thereof;

FIG. 11 is a top view thereof;

FIG. 12 is a bottom view thereof;

FIG. 13 is a rear view thereof; and,

FIG. 14 is a front view thereof.

All broken lines in the above figures are for illustrative purposes only and form no part of the claimed design.

1 Claim, 12 Drawing Sheets

Matter enclosed in heavy brackets [ ] appears in the original patent, but forms no part of this reissue; matter printed in italics indicates the additions made by reissue.
